UNITED STATES PATENT OFFICE.

WILLIAM G. SANDERSON, OF CHICAGO, ILLINOIS.

VALVE SEAL.

1,426,412.

Specification of Letters Patent. Patented Aug. 22, 1922.

Application filed July 14, 1921. Serial No. 484,611.

To all whom it may concern:

Be it known that I, WILLIAM G. SANDERSON, a citizen of the United States, residing at Chicago, in the county of Cook and State of Illinois, have invented certain new and useful Improvements in Valve Seals, of which the following is a specification.

The invention relates to improvements in valve seals.

10 One of the objects of the invention is to provide a valve seal that will visually indicate the fact when the valve has been moved from sealed position.

15 Another object is to provide a seal in which a distinctive part is and will remain covert while the valve is in sealed position and which will automatically be displayed and conspicuously exhibited when the valve has been moved from said position.

20 Another object is to provide a seal in which a card, within an envelope, constitutes part of a link of the seal and in which the card is withdrawn from the envelope in the act of moving the valve from its 25 sealed position.

Another object is to provide a seal in which a card within an envelope, constitutes part of a link of the seal and in which the card is secured to the valve handle by 30 a seal, and in which the envelope is secured to an immovable object by a seal so that upon movement of the valve handle the card is pulled out of the envelope, leaving the card conspicuously displayed and sealed 35 to the handle and leaving the envelope sealed to the fixed object.

The arrangement of the card is such, with respect to the envelope, that it can not be returned to the envelope without showing 40 evidences of its removal.

Another object is to provide an efficient seal for a valve which will interpose very slight resistance to the movement of the valve handle when it becomes necessary to 45 move the valve after it has been sealed.

Other, further and more specific objects of the invention will become readily apparent to persons skilled in the art, from a consideration of the following description, when taken in conjunction with the 50 drawings, wherein:—

Fig. 1 shows a valve and the manner of sealing the wheel or handle so that it may not be moved without rupturing the seal.

55 Fig. 2 shows the valve and seal after the valve wheel or handle has been moved to

open or to close the valve as the exigencies of its use may require.

Fig. 3 shows the lower end of the envelope after the hole, through which the seal wire passes, has been ruptured in the act of withdrawing the card from the envelope due to the rotation of the valve wheel.

In all of the views the same reference characters are employed to indicate similar parts.

In fire protection sprinkler systems, in which automatic sprinkler heads are installed, it is highly desirable that the pipe or riser communicating with the source of water supply, and by which the sprinkler heads are furnished with water, should remain open to permit flow of water to the heads at all times. There are occasions, however, when it becomes imperatively necessary to temporarily interrupt the flow or shut off the water for repairs, and the like, and for this reason a shut off valve is placed in the water supply pipes, or risers.

In systems of this character the most vigilant supervision over the valves must be continuously maintained and to this end some means must be provided to automatically and unfailingly display a conspicuous indication as an evidence of the fact that the valve has been closed and the water supply shut off from the sprinkler heads or a group of sprinkler heads, immediately upon closing the valve.

In the drawings 5—5' shows parts of a riser or water supply pipe. 6 is a valve casing included between the pipe sections within which is contained the valve and parts of the usual shut off valve operable by rotation of the usual valve stem 7. A valve wheel or handle 8, for rotating the stem, is connected thereto by a key 9.

Assuming that the valve is open, as shown in Fig. 1, it becomes necessary to rotate the wheel 8 clockwise several revolutions to close it.

To seal the valve in open position a card 10, shown in Fig. 1 inside the envelope 12, and in Fig. 2 hanging conspicuously from the valve wheel 8, is placed in the envelope 12. The envelope is provided at its closed end with a reinforcing eyelet or grommet 11, through which a seal wire 14 is passed, then secured to a fixed point as a screw eye 15, the two ends being tied together with the usual lead seal 16.

The card 10, which is preferably brilliantly red in color, containing the necessary instructions and directions printed thereon, and having preferably the legend "Sprinklers shut off" appearing on both sides in large type is for permanent attachment to the valve wheel. When the valve is closed the card is brought plainly in sight and when the valve is open the card is enclosed 10 within the envelope and out of sight. The card is provided on one end with a reenforcing eyelet or grommet 17. When the card is placed within the envelope a seal wire 18 is passed through the eyelet and 15 through one, or two registering openings, 19, near the open end of the envelope.

The seal wire 18 is now passed around the rim of the wheel 8 and the lead seal 20 is secured to the wire and made to connect 20 the ends 21 of the seal wire 18.

When the wheel 8 is rotated in valve closing direction to an extent less than one-half of a revolution, the wire 18 will rupture the envelope part surrounding the hole or holes 25 19, and the card will drop out of the envelope into position shown in Fig. 2. The envelope, with proper endorsements thereon, announcing the time when the valve was closed, when opened, and by whom it was 30 opened, is subsequently mailed or otherwise delivered to the supervisors of the system. When the valve is again opened another envelope is furnished and the card enclosed 35 therein as before, and the envelope sealed to the card and wheel and to a suitable point by an authorized supervisor.

The display of the card attached to the wheel is an unfailing indication that the valve is or has been closed and calls for 40 immediate attention.

The rupture at hole 19 prohibits the subsequent use of the envelope to again conceal the card. When the card has been withdrawn from its concealing means to which 45 it is sealed, which may well be an envelope, and replaced therein after opening the valve, the presence of evidence that the seal has been broken, as by tearing the envelope from hole 19, shows that the valve has been closed 50 without reporting the fact to the supervisors in the required manner. The card may be sealed to the concealing means by use of any convenient sealing device that will leave with the concealing means evidence of its 55 rupture.

While I have herein shown a single exemplification of my invention, it will be apparent, to persons skilled in the art, that various changes may be made therein within 60 the scope of the appended claims.

Having described my invention what I

claim as new and desire to secure by Letters Patent, is:—

1. A device of the character described comprising a cover part sealed to a relatively stationary object and a display part connected thereto, normally invisible, sealed to a movable object, arranged to be disconnected from the cover part by movement of said movable object from sealed position, 70 and made visible when disconnected from the cover part.

2. A device of the character described comprising a link element, sealed to a relatively stationary object and another link 75 element connected to the first mentioned element, normally invisible and sealed to a movable object, arranged to be disconnected from the other element by movement of said movable object from its sealed position and 80 made visible when so disconnected.

3. A device of the character described comprising an envelope sealed to a relatively stationary object; a card within the envelope; a relatively movable object and a seal 85 connecting the envelope and card to the movable object whereby to withdraw the card from the envelope when said object is moved.

4. A device of the character described 90 comprising a card cover to conceal a card, sealed to a relatively stationary object and having a hole near its free end; a card concealed thereby having a hole in its outer end substantially registering with the hole in the 95 cover; a valve having a handle, and a seal connected to the handle and passing through said registering holes, whereby to rupture the card cover and withdraw the card when the valve handle is moved from sealed position.

5. A device of the character described comprising an envelope sealed to a relatively stationary object and having a hole near its open end; a card within the envelope having 105 a hole in its outer end; a rotatable valve wheel and a seal passing through the aforesaid holes and enclosing a part of said wheel, whereby to withdraw the card when the wheel is rotated.

6. A device of the character described comprising means for concealing a card, sealed to a stationary object; a card normally concealed by said means; a valve handle sealed to the card whereby to withdraw the card from the concealing means when the handle is moved and a visible indication on the concealing means indicative of movement of said handle.

In testimony whereof I hereunto subscribed my name.

WILLIAM G. SANDERSON.
